UNITED STATES PATENT OFFICE.

JOHN T. REED, OF ST. JOHN, NEW BRUNSWICK, CANADA.

DESIGN FOR A PHOTOGRAPH-FRAME SUPPORT.

Specification forming part of Design No. **11,249**, dated June 17, 1879; application filed May 16, 1879.
[Term of patent 3½ years.]

To all whom it may concern:

Be it known that I, JOHN T. REED, of St. John, New Brunswick, Canada, have invented a new Design for Photograph-Frame Support, of which the following is a specification.

The design is represented in the accompanying drawing by a perspective view of the support.

A is the stand or support, and is slotted at b to receive the frame. It is formed with flat sides, perforated at c c, and curved edges, terminating at each end in semicircular knobs e e, and a recessed central portion, d, of semicircular form. A thin spring, m, is inserted in the slot.

From each side of the semicircular knobs e e at each end there project short pieces g g, with chamfered edges h h.

The stand or support consists of one piece,

and is intended to be adjusted or applied to the bottom of frames, midway between the outsides of same.

Having thus described my invention, what I claim as new, and desire to secure by Letters Patent, is—

A design for a photograph-frame support, which consists of the support A, formed with flat sides, perforated at c c, and curved edges, terminating at each end in semicircular knobs e e, and a recessed central portion, d, of semicircular form, a thin spring, m, and projecting pieces g g, with chamfered edges h h, as shown and described.

JOHN TWELLS REED.
